UNITED STATES PATENT OFFICE.

JOSEPH W. DICKINSON, OF CRANFORD, NEW JERSEY, ASSIGNOR TO THE SCHUBERT PIANO COMPANY, OF NEW YORK, N. Y., A CORPORATION OF NEW YORK.

SHEET-GUIDING MECHANISM.

1,098,891.

Specification of Letters Patent.

Patented June 2, 1914.

Application filed April 7, 1913. Serial No. 759,266.

To all whom it may concern:

Be it known that I, JOSEPH W. DICKINSON, a citizen of the United States, residing at Cranford, in the county of Union and State of New Jersey, have invented certain new and useful Improvements in Sheet Guiding Mechanism, of which the following is a specification.

This invention relates to tracking or sheet guiding mechanism for automatic player instruments, such as automatic pianos, and it more particularly relates to improved pneumatic mechanism for controlling the movement of sheets or webs, such for instance as perforated music sheets, the object of the invention being to provide an improved mechanism of this character simple in its construction and positive in its action, and by means of which the music sheet will be automatically maintained in its proper position relatively to the tracker board or bar so that the perforations of the music sheet will properly coincide or track with the corresponding perforations or apertures of the tracker board during the playing of the instrument, and which mechanism may also be readily adjusted to correspond with different widths of music sheets, the present organization being in part an improvement upon that shown and described in my contemporaneously pending applications.

An object of the present improvement is the provision of an improved mechanism of this kind in which the necessity of using an adjustable port is avoided, while all the advantages of such an adjustable port are retained.

Where an adjustable port is used, if it is accidentally struck by the hand and thrown out of its proper adjustment the operator sometimes fails to re-adjust it into its proper position. By the present organization, however, it is not possible to throw the port out of its proper position, so that after it is once adjusted by the manufacturer it does not have to be re-adjusted.

Another object of the invention is to provide an improved mechanism of the character described in which the necessity of using the valve box shown in my contemporaneously pending application Serial No. 680,399, filed February 28, 1912, is done away with, while all the advantages of the construction

described in said application are retained in the use of either form of the improvement herein shown; that is to say, on the cessation of the pumping operation the music sheet will not be moved to one side or the other by the further action of the pneumatics, so that it will remain in the position in which it was when the traveling movement of the sheet ceased, and in which the necessity of providing a port at each end of the tracker bar, or two valve-controlled ports, one at each side of the music sheet, is avoided.

The present improvement includes a double pneumatic, which may be connected with one of the music rolls by a positively acting cam, as shown in the said application hereinbefore referred to if desired.

The present mechanism is so organized and constructed that should the edge of the music sheet opposite to the valve-controlled port be mutilated the operation of the mechanism will not be interfered with. In other words, where ports are provided at each end of the tracker bar for engagement by the traveling web, or where valve-controlled levers are located at each side of the music sheet to be engaged thereby, it follows that if one edge of the sheet is torn or mutilated the mechanism will be operated prematurely at times, although the perforations therein may be in perfect registration with the tracker board perforations, and the sheet so be thrown out of register. In the present mechanism, however, it is not necessary that both edges of the sheet be in perfect condition.

In the drawings accompanying and forming part of this specification, Figure 1 is a perspective view of this improved mechanism as the same may be applied to a piano-forte, the mechanism for rotating the music sheet rolls being omitted, as this is well known and common; Fig. 2 is a detail view of the port and its movable valve. This figure is intended to show the position of the valve while the machine is being played, in other words when the sheet is in position across the tracker bar and pumping is proceeding. Fig. 3 is a perspective view of another form of this improved mechanism; Fig. 4 is a detail view of the ports and valve-lever as used in connection with the form of pneumatics shown in Fig. 3; Fig. 5 is a rear

view of the double pneumatic shown in Fig. 3. And Fig. 6 is a vertical sectional view of the double pneumatic shown in Fig. 1 illustrating how the tubes 21, 26, 27, and 28 are connected therewith.

Similar characters of reference indicate corresponding parts in the different figures of the drawings.

The present improvement is particularly adapted for self-playing instruments, and in the present embodiment thereof it is shown constructed for that purpose. The music rolls are preferably carried by a suitable casing or box 2 of any desired construction. The music roll 3 carrying the record or sheet which is to travel over the perforated tracker board 5 is located between a pair of bearing members 6 and 7 carried at opposite ends of the casing. The bearing member 6, fixedly secured at one side of the casing, includes a spring plunger 8 having a socket 9 for the reception of one end of the shaft of the music roll 3. The bearing member 7 may be formed like that shown and described in my contemporaneously pending application and therefore no further description thereof is deemed necessary. The spring pressed plunger 8 acts to maintain the music roll shaft in engagement with the bearing member 7, and this is the main purpose of such spring actuated plunger. The take up roll 11 is suitably supported at the opposite side of the tracker board, and these two rolls are operated by suitable driving mechanism which, as hereinbefore stated, it is not necessary to show because well known and common.

In the form shown in Fig. 1, the casing or box supports a valve-controlled port, comprising a bracket or arm 10 having at one end a port 12 having a conduit connection with the double pneumatic hereinbefore referred to. This port is fixed so that it usually has no adjustment at all. Closing this port is a valve 14 carried by a pivoted lever 15, and connected with the bracket by a light spring 16. The forward end 17 of this lever is provided with an adjusting device or screw 18 for engagement with an adjustable member 19 shown in the form of a leaf spring having its inner end riveted or otherwise connected to the valve lever 15, the outer end of this spring being in position to be engaged by the edge of the music sheet and therefore it and its adjusting screw project beyond the tracker bar, the lever and its leaf spring extending through an opening 20 therein, the valve lever and port being maintained in proper co-operative relation by means of the coiled spring 16 hereinbefore described. By adjusting the leaf spring carried by the valve lever it will be brought into position to engage the music sheet and also it will enable various widths of music sheets to be used in the

apparatus or permit the transposition of the key of the music to be readily accomplished. From this port 12 a conduit or tube 21 leads to a pneumatic A in a similar manner to that shown and described in my contemporaneously pending application, so that a further description thereof is not deemed necessary herein.

The pneumatic A is a double pneumatic, comprising a pneumatic A' and a pneumatic A'', one at each side of a partition or rigid portion 22 secured at its lower end to any suitable support, preferably adjacent to the tracker board casing. These two pneumatics A' and A'' are connected together by a bracket 23 so that they will move in unison, in other words one will contract while the other is expanding. Connected to these pneumatics is a valve chamber or box 24 having an opening 25 at one part, as at its top, which may be covered with a suitable porous material to permit the passage of atmospheric air into the box. As this valve box is similar to that shown and described in my contemporaneously pending application, a further description thereof is not deemed necessary.

The valve box 24 has one part thereof connected by a tube 25' with the main pumping bellows. The double pneumatic is connected with the valve box by a conduit 26, which has connection with a T-shaped coupling to which the conduit 21 leading from the port 12 hereinbefore described is connected. The valve box is also connected by a conduit 27 with the pneumatic A' and is also connected by a conduit 28 with the pneumatic A''. A small bleeder hole may be formed adjacent to the point where the conduit leading from the valve box communicates with the pneumatic A'.

In practice the valve lever may be held in such position relatively to its port that it will just slightly bleed.

In operation the valve lever will be maintained in its normal position when the music sheet is properly tracking. Should the sheet move to the right the port will be closed and the mechanism so operated that the sheet will be returned to its proper tracking position. Should the sheet move to the left it will further open the port and the mechanism will then be operated to return the sheet to its proper position.

From the foregoing it will be observed that the sheet is thus positively maintained in its proper registering position on the tracker board at all times by being shifted either to the right or to the left as occasion may require, and this by means of a single port at one side of the sheet, which port it is not necessary should be adjusted.

In the form shown in Figs. 3, 4 and 5, the valve box hereinbefore referred to is dispensed with and a pair of ports provided,

one of which is fixed and the other yieldable, and intermediate which ports a movable valve lever is located, both of these ports being connected with the double pneumatic. 5 In this organization the music sheet rolls and their casing, the tracker bar etc. are substantially similar to that hereinbefore described. The double pneumatic is also substantially similar, except that the conduit 10 connections therewith are slightly different. Carried by the casing is a fixed port 30 carried by a bracket or arm 31 similar to that hereinbefore described, and coöperating therewith is a valve 32 carried by a valve 15 lever 33 similar to that hereinbefore described, so that no further description thereof is necessary. Carried by the support to which the port just described is secured, is a pivoted port 34, this being carried by an 20 arm or lever 35 pivotally secured to said support, a stop 36 limiting the inward movement of this lever. Connected with this pivoted port is a conduit 37 running to the pneumatic A', the other port having a conduit 38 running to the pneumatic A''. In 25 this form of the improvement it will be observed that there is a port at each side of the valve lever, one being fixed while the other is pivoted for swinging movement, a spring 40 connecting the two and effective 30 to hold the yielding port 34 in engagement with the stop pin 36, so that the necessity of having the valve box shown in Fig. 1 is done away with. The spring 16 tends to 35 pull the valve lever up adjacent to the fixed port 30. If the swinging or yielding port were stationary it follows that when the music sheet moved the forward end of the valve lever to the left the valve thereof 40 would strike against the port 34 and consequently, as there would be no "give" to it, the paper would be torn. But by mounting this port 34 so that it will yield the port will thus give and so permit the paper to 45 push the valve lever farther over. As soon as the valve of this lever touches the yielding port the mechanism commences to return the paper into its proper position. When the paper is tracking properly these 50 two ports will be slightly open or bleeding, the valve lever being between the two so as to give an equal pressure on the bellows of the double pneumatic. When the paper moves to the right the fixed port will be 55 closed, so that the pneumatic will operate in the regular way to move the sheet roll.

From the foregoing it will be observed that by the provision of a pair of pneumatics operating in the manner described 60 the action of one counterbalances that of the other so that there is maintained an equilibrium to properly maintain the sheet in its correct position relatively to the tracker bar.

65 It will be understood that the various de-

tails may be more or less changed without departing from the gist of this invention or the spirit and scope thereof.

In the double pneumatic shown in Fig. 5 a bleeder hole 42 is located at the lower end 70 of the pneumatic, this being in communication with both the pneumatics A' and A''.

The music roll does not necessarily have to travel over the tracker-bar for the valve to be in the position shown in Fig. 2, but the 75 music sheet has to be over the tracker-bar and pumping must be going on. This figure is intended to show the port slightly bleeding and balancing both pneumatics. The music roll sheet is however over the tracker 80 bar. When the machine is inoperative the spring 16 will pull the valve over against the port 12, that is when no pumping is going on, and the valve will be closed. When the music sheet is in position or is 85 passing over the tracker-bar and the instrument is being pumped the edge of the music sheet presses against the part 19 by reason of the pneumatics and holds the valve 14 slightly open or bleeding which balances the 90 pneumatics, which in turn control themselves by controlling the pressure of the paper against the lever spring 19. Of course, the spring 16 is properly constructed to permit 95 this action.

I claim as my invention:

1. In an apparatus of the class described, the combination with a perforated tracker bar and sheet rolls adapted to carry a perforated music sheet, of means operative to 100 shift one of said parts relatively to another to insure the proper registration of the sheet perforations with those of the tracker bar, said means including a port, a swinging lever having a valve coöperating with said port and an adjustable member fixed to said valve lever and in position between said lever and the edge of the sheet to be engaged by the edge of the sheet.

2. In an apparatus of the class described, the combination with a perforated tracker bar and sheet rolls adapted to carry a perforated music sheet, of means operative to 110 shift one of said parts relatively to another to insure the proper registration of the sheet perforations with those of the tracker bar, said means including a port, a swinging lever having a valve coöperating with said port and an adjustable member fixed to said valve lever and in position between said lever and the edge of the sheet to be engaged by the edge of the sheet, said adjustable member comprising a spring.

3. In an apparatus of the class described, the combination with a perforated tracker bar and sheet rolls adapted to carry a perforated music sheet, of means operative to 120 shift one of said parts relatively to another to insure the proper registration of the sheet perforations with those of the tracker bar,

125

said means including a bleeding port, a swinging lever having a valve coöperating with said port and an adjustable member fixed to said valve lever and in position to be engaged by the edge of the sheet, said adjustable member comprising a spring.

4. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a double pneumatic, a port, a swinging lever having a valve coöperating with said port and an adjustable member fixed to said valve lever and in position between said lever and the edge of the sheet to be engaged by the edge of the sheet.

5. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a port located away from the sheet, a swinging lever having a valve coöperating with said port said valve being located at the rear end of the swinging lever, and an adjustable member fixed to said valve lever and in position to be engaged by the edge of the sheet.

6. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a bleeding port, a swinging lever having a valve coöperating with said port and an adjustable member fixed to said valve lever and adapted to be engaged by the edge of the sheet.

7. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a double pneumatic, a bleeding port, a swinging lever having a valve coöperating with said port and an adjustable member fixed to said valve lever and adapted to be engaged by the edge of the sheet.

8. In an apparatus of the class described, the combination with a perforated tracker bar and sheet rolls adapted to carry a perforated music sheet, of means operative to shift one of said parts relatively to another to insure the proper registration of the sheet perforations with those of the tracker bar,

said means including a bleeding port, a movable lever having a valve coöperating with said port and an adjustable member fixed to said valve lever and in position to be engaged by the edge of the sheet.

70

9. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a fixed bleeding port, a movable lever, having a valve coöperating with said port, a spring fixed to said valve lever and in position to be engaged by the edge of the sheet, and means for adjusting said spring relatively to said valve lever.

75

10. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a bleeding port, a movable valve coöperating with said port, a member coöperating with said valve and in position to be engaged by the edge of the sheet, and means for adjusting said member relatively to said valve.

85

11. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a port, a lever having a valve coöperating with said port, a member fixed to said valve lever at the side nearest to the edge of the music sheet and in position to be engaged by the edge of the sheet, and means for adjusting said member relatively to said valve and comprising an adjusting screw.

100

12. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a bleeding port, a pivoted valve lever carrying a valve coöperating with said port, a spring fixed to said valve lever and in position to be engaged by the edge of the sheet, and an adjusting screw carried by the valve lever for adjusting said spring.

115

13. In an apparatus of the class described, the combination with a perforated tracker bar and sheet rolls adapted to carry a perforated music sheet, of means opera-

130

to insure the proper registration of the sheet perforations with those of the tracker bar, said means including a double pneumatic, a pair of bleeding ports one yieldable relatively to the other, and a valve located between and coöperating with said ports and having a part in position to be engaged by the edge of the sheet.

23. In an apparatus of the class described, 10 the combination with a perforated tracker bar and sheet rolls adapted to carry a perforated music sheet, of means operative to shift one of said parts relatively to another to insure the proper registration of the 15 sheet perforations with those of the tracker bar, said means including a pair of ports one yieldable relatively to the other, a swinging valve located between and coöperating with said ports, and an adjustable 20 member carried by said valve and adapted to be engaged by the edge of the sheet.

24. In an apparatus of the class described, the combination with a perforated tracker 25 bar and sheet rolls adapted to carry a perforated music sheet, of means operative to shift one of said parts relatively to another to insure the proper registration of the sheet perforations with those of the tracker bar, said means including a pair of ports 30 one yieldable relatively to the other, a swinging valve located between and coöperating with said ports, and an adjustable member carried by said valve and adapted to be engaged by the edge of the sheet, said 35 adjustable member comprising a spring.

25. In an apparatus of the class described, the combination with a perforated tracker bar and sheet rolls adapted to carry a perforated music sheet, of means operative to 40 shift one of said parts relatively to another to insure the proper registration of the sheet perforations with those of the tracker bar, said means including a pair of ports one yieldable relatively to the other, a swinging 45 valve located between and coöperating with said ports, and an adjustable member carried by said valve and adapted to be engaged by the edge of the sheet, said adjustable member comprising a spring and 50 means for adjusting it and comprising a screw carried by said valve.

26. In an apparatus of the class described, the combination with a perforated tracker bar having an opening at one end thereof 55 and sheet rolls adapted to carry a perforated music sheet, of means operative to shift one of said parts relatively to another to insure the proper registration of the sheet perforations with those of the tracker bar, said means including a pair of ports one yieldable relatively to the other, a double pneumatic connected with said ports, and a swinging valve lever having a valve located between and coöperating with said

ports, said lever projecting through the 65 opening in said tracker bar and having a part in position to be engaged by the edge of the sheet.

27. In an apparatus of the class described, the combination with a perforated tracker 70 bar having an opening at one end thereof and sheet rolls adapted to carry a perforated music sheet, of means operative to shift one of said parts relatively to another to insure the proper registration of the sheet 75 perforations with those of the tracker bar, said means including a pair of ports one yieldable relatively to the other, a double pneumatic connected with said ports, and a swinging valve lever having a valve located 80 between and coöperating with said ports, said lever projecting through the opening in said tracker bar and having a part in position to be engaged by the edge of the sheet, said part comprising an adjustable 85 member.

28. In an apparatus of the class described, the combination with a perforated tracker bar having an opening at one end thereof and sheet rolls adapted to carry a perforated music sheet, of means operative to shift one of said parts relatively to another to insure the proper registration of the sheet perforations with those of the tracker bar, said means including a pair of ports one 95 yieldable relatively to the other, a double pneumatic connected with said ports, and a swinging valve lever having a valve located between and coöperating with said ports, said lever projecting through the opening 100 in said tracker bar and having a part in position to be engaged by the edge of the sheet, said part comprising an adjustable member consisting of a spring fixed to said valve lever and means carried by said lever 105 for adjusting said spring.

29. In an apparatus of the class described, the combination with a perforated tracker bar and sheet rolls adapted to carry a perforated music sheet, of means operative to 110 shift one of said parts relatively to another to insure the proper registration of the sheet perforations with those of the tracker bar, said means including a double pneumatic, a pair of ports connected with said pneumatic, and a swinging valve lever having the valve thereof in position to control said ports and a part thereof in position to be 115 engaged by the edge of the sheet.

30. In an apparatus of the class described, 120 the combination with a perforated tracker bar and sheet rolls adapted to carry a perforated music sheet, of means operative to shift one of said parts relatively to another to insure the proper registration of the sheet 125 perforations with those of the tracker bar, said means including a double pneumatic, a pair of bleeding ports connected with said

- 5 tive to shift one of said parts relatively to another to insure the proper registration of the sheet perforations with those of the tracker bar, said means including a fixed 50 arm carrying a port located away from the sheet, a lever pivoted between its ends and carrying a valve coöperating with said port, a spring for said valve lever, a spring fixed to said valve lever and in position to be engaged by the edge of the sheet.
- 10 55 14. In an apparatus of the class described, the combination with a perforated tracker bar and sheet rolls adapted to carry a perforated music sheet, of means operative to shift one of said parts relatively to another to insure the proper registration of the sheet 60 perforations with those of the tracker bar, said means including a pair of ports one yieldable relatively to the other, and a valve located between and coöperating with said ports and having a part in position to be engaged by the edge of the sheet.
- 15 65 15. In an apparatus of the class described, the combination with a perforated tracker bar and sheet rolls adapted to carry a perforated music sheet, of means operative to shift one of said parts relatively to another to insure the proper registration of the sheet 70 perforations with those of the tracker bar, said means including a fixed port located behind the sheet, a pivoted lever having a valve at its rear end coöperating with said port, said lever having its 75 forward end projecting forwardly of the tracker bar, a member fixed to said lever and in position to be engaged by the edge of the sheet, and means carried by said lever for adjusting said member.
- 20 80 16. In an apparatus of the class described, the combination with a perforated tracker bar having an opening therethrough at one end and sheet rolls adapted to carry a perforated music sheet, of means operative to shift one of said parts relatively to another to insure the proper registration of the sheet 85 perforations with those of the tracker bar, said means including a port, a swinging lever having a valve at its rear end coöperating with said port, said lever projecting through said tracker bar opening, and an adjustable member fixed to said valve lever and in position to be engaged by the edge of the sheet.
- 25 90 17. In an apparatus of the class described, the combination with a perforated tracker bar having an opening therethrough at one end and sheet rolls adapted to carry a perforated music sheet, of means operative to shift one of said parts relatively to another to insure the proper registration of the sheet 95 perforations with those of the tracker bar, said means including a double pneumatic, a port, a swinging lever having a valve coöperating with said port, said lever projecting through said tracker bar opening, and an adjustable member fixed to said valve lever at the side nearest to the music sheet and in position to be engaged by the 100 edge of the sheet.
- 30 100 18. In an apparatus of the class described, the combination with a perforated tracker bar and sheet rolls adapted to carry a perforated music sheet, of means operative to shift one of said parts relatively to another to insure the proper registration of the sheet 105 perforations with those of the tracker bar, said means including a double pneumatic, a bleeding port, a swinging lever having a valve coöperating with said port, said lever projecting to the front of said tracker bar, and an adjustable member fixed to said valve lever and adapted to be engaged by the edge of the sheet.
- 35 110 19. In an apparatus of the class described, the combination with a perforated tracker bar and sheet rolls adapted to carry a perforated music sheet, of means operative to shift one of said parts relatively to another to insure the proper registration of the sheet 115 perforations with those of the tracker bar, said means including a pair of ports one yieldable relatively to the other, and a valve located between and coöperating with said ports and having a part in position to be engaged by the edge of the sheet.
- 40 120 20. In an apparatus of the class described, the combination with a perforated tracker bar and sheet rolls adapted to carry a perforated music sheet, of means operative to shift one of said parts relatively to another to insure the proper registration of the sheet 125 perforations with those of the tracker bar, said means including a double pneumatic, a pair of ports one yieldable relatively to the other, and a valve located between and coöperating with said ports and having a part in position to be engaged by the edge of the sheet.
- 45 130 21. In an apparatus of the class described, the combination with a perforated tracker bar and sheet rolls adapted to carry a perforated music sheet, of means operative to shift one of said parts relatively to another to insure the proper registration of the sheet 135 perforations with those of the tracker bar, said means including a pair of bleeding ports one yieldable relatively to the other, and a valve located between and coöperating with said ports and having a part in position to be engaged by the edge of the sheet.
- 50 140 22. In an apparatus of the class described, the combination with a perforated tracker bar and sheet rolls adapted to carry a perforated music sheet, of means operative to shift one of said parts relatively to another to insure the proper registration of the sheet 145 perforations with those of the tracker bar, said means including a double pneumatic, a bleeding port, a swinging lever having a valve coöperating with said port, said lever projecting to the front of said tracker bar, and an adjustable member fixed to said valve lever and adapted to be engaged by the edge of the sheet.

- pneumatic, and a swinging valve lever having the valve thereof in position to control said ports and a part thereof in position to be engaged by the edge of the sheet.
31. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a pair of ports located behind the sheet, and a pivoted valve lever coöperating with said ports and having a part projecting into position to have a part thereof engaged by the edge of the sheet.
32. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a pair of ports one a fixed port and the other a swinging port, and a pivoted valve lever in position to control said ports and having a part in position to be engaged by the edge of the sheet.
33. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a pair of ports one a fixed port and the other a swinging port, a pivoted valve lever in position to control said ports and having a part in position to be engaged by the edge of the sheet, and a stop for limiting movement of said swinging port in one direction.
34. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a pair of ports one a fixed port and the other a swinging port, a pivoted valve lever in position to control said ports and having a part in position to be engaged by the edge of the sheet, a stop for limiting movements of said swinging port in one direction, a spring carried by said valve lever for maintaining it in one position, and a spring between said ports for drawing the swinging port toward the fixed port.
35. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a pair of ports one a fixed port and the other a swinging port, a pivoted valve lever in position to control said ports and having a part in position to be engaged by the edge of the sheet, a stop for limiting movement of said swinging port in one direction, a spring carried by said valve lever for maintaining it in one position, and a spring between said ports for drawing the swinging port toward the fixed port.
36. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a fixed port, a swinging port, and a swinging valve lever for controlling said ports and having a part thereof in position to be engaged by the edge of the sheet.
37. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a double pneumatic, a fixed port, a swinging port, and a swinging valve lever for controlling said ports and having a part thereof in position to be engaged by the edge of the sheet.
38. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a double pneumatic, a fixed port, a swinging port, and a swinging valve lever for controlling said ports and having a part thereof in position to be engaged by the edge of the sheet, said part comprising an adjustable spring.
39. In an apparatus of the class described, the combination with a perforated tracker bar and sheet rolls adapted to carry a perforated music sheet, of means operative to shift one of said parts relatively to another to insure the proper registration of the sheet perforations with those of the tracker bar, said means including a double pneumatic, a pair of port carrying members one fixed against movement and the other pivotally supported, a stop for limiting movement of the pivotally supported port, a spring for holding said pivoted port in engagement.

with its stop, a pivoted valve lever having a valve located between and coöperating with said ports, a spring carried by said valve lever and in position to be engaged by the edge of the sheet, and means carried by said valve lever for adjusting said sheet engaging spring.

40. In an apparatus of the class described, the combination with a perforated tracker 10 bar and sheet rolls adapted to carry a perforated music sheet, of means operative to shift one of said parts relative to another to insure the proper registration of the sheet perforations with those of the tracker 15 bar, said means including a port, a swinging lever pivoted intermediate its ends and having a valve at one side of said pivot coöperating with said port, and a member coöperating with said valve lever and adjustable from a point at the opposite side of 20 said pivot and in position to be engaged by the edge of the sheet.

41. In an apparatus of the class described, the combination with a perforated tracker 25 bar and sheet rolls adapted to carry a perforated music sheet, of means operative to shift one of said parts relative to another to insure the proper registration of the sheet perforations with those of the tracker bar, said means including a bleeding port, a swinging lever pivoted intermediate its ends and having a valve rearwardly of its pivotal point for engaging said port and having at the forward side of said pivotal point a 30 spring in position between said lever and the edge of the sheet to be engaged by the edge of said sheet, and means carried by said valve lever forwardly of its pivotal point for adjusting said spring.

40. 42. In an apparatus of the class described, the combination with a perforated tracker bar and sheet rolls adapted to carry a perforated music sheet, of means operative to shift one of said parts relative to another 45 to insure the proper registration of the sheet perforations with those of the tracker bar, said means including a port, a single movable lever having a valve coöperating with said port, and an adjustable member coöperating 50 with said valve lever and in position to be engaged by the edge of the sheet, said single movable valve lever only and its coöperative parts regulating the adjustment of the music sheet in both directions.

55. 43. In an apparatus of the class described, the combination with a perforated tracker bar and sheet rolls adapted to carry a perforated music sheet, of means operative to shift one of said parts relative to another to 60 insure the proper registration of the sheet perforations with those of the tracker bar, said means including a port, a single movable lever having a valve coöperating with said port, and an adjustable member coöp-

erating with said valve lever and in position to be engaged by the edge of the sheet, 65 said adjustable member comprising a spring, said single movable valve lever only and its coöperative parts regulating the adjustment of the music sheet in both directions. 70

44. In an apparatus of the class described, the combination with a perforated tracker bar and sheet rolls adapted to carry a perforated music sheet, of means operative to shift one of said parts relative to another to insure the proper registration of the sheet perforations with those of the tracker bar, 75 said means including a port, a swinging lever having a valve coöperating with said port, a movable member fixed to said valve lever and in position to be engaged by the edge of the sheet, and means located in front of the tracker bar for adjusting said movable member relatively to the valve lever.

45. In an apparatus of the class described, 85 the combination with a perforated tracker bar and sheet rolls adapted to carry a perforated music sheet, of means operative to shift one of said parts relative to another to insure the proper registration of the sheet 90 perforations with those of the tracker bar, said means including a bleeding port, a single swinging lever having a valve coöperating with said port, and an adjustable member fixed to said valve lever and in position 95 to be engaged by the edge of the sheet.

46. In an apparatus of the class described, the combination with a perforated tracker bar and sheet rolls adapted to carry a perforated music sheet, of means operative to 100 shift one of said parts relative to another to insure the proper registration of the sheet perforations with those of the tracker bar, said means including a bleeding port, a single swinging lever having a valve coöperating 105 with said port, and an adjustable member fixed to said valve lever and in position to be engaged by the edge of the sheet and comprising a spring.

47. In an apparatus of the class described, 110 the combination with a perforated tracker bar and sheet rolls adapted to carry a perforated music sheet, of means operative to shift one of said parts relative to another to insure the proper registration of the sheet 115 perforations with those of the tracker bar, said means including a bleeding port, a single swinging lever having a valve coöperating with said port, an adjustable member fixed to said valve lever and in position to 120 be engaged by the edge of the sheet and comprising a spring, and means carried by the valve lever in front of the tracker bar for adjusting said adjustable member relatively to said valve lever.

48. In an apparatus of the class described, 125 the combination with a perforated tracker bar and sheet rolls adapted to carry a per-

forated music sheet, of means operative to shift one of said parts relative to another to insure the proper registration of the sheet perforations with those of the tracker bar, 5 said means including a double pneumatic, a bleeding port, a single swinging lever having a valve cooperating with said port, an adjustable member fixed to said valve lever and in position to be engaged by the edge of the sheet, and means located in front of 10 the tracker bar for adjusting said adjustable member relatively to the valve lever.

Signed at New York city, this 2nd day of April, 1913.

JOSEPH W. DICKINSON.
